Primary Examiner — Philip S Hyder*Assistant Examiner* — Darlington Ly(74) *Attorney, Agent, or Firm* — Faegre Baker Daniels LLP(57) **CLAIM**

The ornamental design for a side-by-side all terrain vehicle, as shown and described.

DESCRIPTION

FIG. 1 is a front and left side perspective view of the side-by-side all terrain vehicle;

FIG. 2 is a rear and right side perspective view thereof;

FIG. 3 is a left side elevation view thereof;

FIG. 4 is a right side elevation view thereof;

FIG. 5 is a top plan view thereof;

FIG. 6 is a front elevation view thereof; and,

FIG. 7 is a rear elevation view thereof.

The broken lines shown in the drawings illustrate portions of the side-by-side all terrain vehicle that form no part of the claimed design.
